UNITED STATES PATENT OFFICE.

EDWARD MINGAY, OF BOSTON, MASSACHUSETTS, ASSIGNOR TO BOSTON
AND MAINE FOUNDRY COMPANY, OF SAME PLACE.

DESIGN FOR A COOKING-STOVE.

Specification forming part of Design No. **6,965**, dated October 21, 1873; application filed September 3, 1873.
[Term of Patent 7 years.]

To all whom it may concern:

Be it known that I, EDWARD MINGAY, of Boston, in the county of Suffolk and State of Massachusetts, have invented an Improved Design for a Cooking-Stove or Range; and I do hereby declare that the following, taken in connection with the drawings which accompany and form part of this specification, is a description of my invention sufficient to enable those skilled in the art to practice it.

The invention or design relates to the general and specific ornamentation of the main plates, panels, and doors of cooking-stoves or ranges, and may be understood by reference to the drawing, which shows in front elevation a stove or range embodying the design.

The fire-pot doors *a b*, the ash-pit door *c*, the oven-door *d*, and the warm-closet door *e*, are all shown as having upon each a center piece or panel, *f*, surrounded by a rectangular or parallel-sided border, *g*, with ornamenteally-angled corners, *h*, each panel having in its

center a medallion or other ornamental piece, *i*, and the space between each line of the border *g* and the edge of the door being ornamented by a long beaded line, *x*, at the center of which is a larger bead, *k*, and the upper corners of each door so ornamented being rounded, as seen at *o*. Besides these ornaments, there are shown corner ornaments *l* and hinge ornaments *m*, and also a molding ornament, *n*.

What I claim as my invention is—

The design for stove-doors and stove-plates and panels, composed of the center-piece *f*, border *g*, corners *h*, center medallion *i*, beaded line *x k*, and corners *o*, substantially as shown and described.

Executed this 23d day of August, A. D. 1873.

EDWARD MINGAY.
